UNITED STATES PATENT OFFICE.

JASPER BLACKBURN, OF WEBSTER GROVES, MISSOURI.

CABLE-HANGER.

1,240,169.

Specification of Letters Patent. Patented Sept. 18, 1917.

Application filed October 11, 1915. Serial No. 55,245.

To all whom it may concern:

Be it known that I, JASPER BLACKBURN, a citizen of the United States, and resident of Webster Groves, Missouri, have invented 5 certain new and useful Improvements in Cable-Hangers, of which the following is a specification containing a full, clear, and exact description, reference being had to the accompanying drawings, forming a part 10 hereof.

My invention relates to improvements in cable hangers wherein a support is provided, for a cable, having means for suspension from a messenger and means for holding 15 the suspending means against movement lengthwise relative to the messenger.

The object of my invention is to construct a device of spring wire for the support of aerial cables suspended from a messenger or 20 span wire which may be applied without the use of tools to existing lines and which is designed to prevent kinking of the cable and to be locked to the messenger or span wire to preserve spacing.

With the above object in view my invention relates to certain novel details of construction and arrangement of parts, herein-after fully set forth, pointed out in my 25 claims and illustrated by the accompanying drawings, in which—

Figure 1 is a plan of one of my improved cable hangers as applied to a messenger:

Fig. 2 is an elevation of the hanger as applied to a messenger and shows by dotted 30 lines a cable supported by the hanger; and

Fig. 3 is an end view of the hanger as shown in Fig. 2 looking toward the locking end.

Referring by numerals to the accompanying 35 drawings, 5 designates the body of the hanger which is of cradle formation, that is, comprises the spaced fingers A, B and C upon which the cable 6 shown only by dotted lines, is supported at more than one 40 point to maintain it in a straight line in order to obviate kinking as is common in the support of leaden cables.

As shown the entire structure is made up 45 from a single piece of material, preferably 50 steel wire, and hence the fingers A, B and C of the cradle like body are joined by the curved portions 7 and 8. By preference, also, the fingers A, B and C are dished as shown 55 in Fig. 3 to conform more nearly with the cable and to present a relatively long bear-

ing surface for the cable which further tends to obviate cable bending or kinking.

Arising from and forming integral continuations of the fingers A and C, of the cradle like cable supporting body, are the 50 arms 9 and 10, the arm 10 terminating with a hook 11 whereby it may suspend from a messenger or span wire 12 and the arm 9 having at its uppermost end an integral wrist or substantially straight portion 13, 55 which carries at its free end a hook 14, which is a companion to the hook 11 and constitutes therewith the means for suspending the hanger from the messenger or span wire, and also provides the means for locking 70 the hanger on the messenger wires.

The eyes or loops formed by the hooks 11 and 14 bear relatively alined relationship to the end that the cradle like cable supporting body is held parallel with the messenger 75 but are of different angular relationship with the axis of the messenger or span wire, the hook 11 being substantially at right angles to the span wire while the hook 14 bears an obtuse angular relationship with the 80 messenger, whereby its terminal may be spaced from the wrist to permit the introduction of the span wire therebetween.

As shown in Fig. 2 the wrist 13 is shown 85 to be substantially parallel with the span wire, which is its true position when applied, but it is to be understood that normally this wrist inclines downwardly and outwardly from the arm 9 to the hook 14 and occupies a plane, relative to the plane 90 of the fingers A, B and C higher than the hook 11, thus necessitating a bodily strain of the entire structure including the cradle like body and the wrist 13 to place the two hooks 11 and 14 over a span wire. The substantially straight portion or wrist 13 carried by the arm 9 is of greater length than the diameter of the span wire, and when the hanger is in use said portion extends at an 95 angle to the longitudinal axis of the span wire, and exerts a yielding upward pressure on the underneath surface thereof. The said portion 13 contacts on the underneath surface of the span wire and the bent over or overlying portion of the hook 14 contacts 100 with the upper surface of the span wire at a point beyond or laterally removed from the contacting point of the portion 13 of the span wire and exerts a downward pressure 105 thereon. When the hanger is applied, as 110

shown in Fig. 1, it will be observed that not only the portion 13 occupies an angle other than a right angle to the longitudinal axis of the span wire, but the portion of the hook 5 overlying the span wire is also arranged at an angle other than a right angle to the span wire, and at an angle to the portion 13.

It is to be observed further that the wrist 13 in addition to the incline just referred to 10 stands at an angle relative to the span wire, and is substantially at right angles to the hook 14 thereby causing the hook to be torsionally clamped to the span wire.

By this arrangement of the parts, it is obvious 15 that the hanger may be applied to existing span wires and cables.

In applying my device the hook 14 is first placed over the span wire, with the body and the other hook 11 swung laterally from 20 the span so that the cable may rest between the arms 9 and 10 and over the fingers A, B and C.

With the cable thus resting the entire hanger is swung to bring the hook 11 to position 25 on the span wire, that is, the entire structure is swung on the hook 14, to bring the hook 11 to position on the cable, which necessarily springs the wrist 13 both laterally and vertically relative the span wire 30 thereby causing the wrist 13 as well as the hook 14 to bind against the span wire and thus hold the hanger against movement whereby to preserve relative spacing.

Having thus described my invention, what 35 I claim as new therein is:

1. A cable hanger comprising spaced fingers arranged to support, but not surround a cable, arms spaced apart and curved in opposite directions formed integral with certain of said fingers, a hook carried by one 40 of said arms, and a yielding clamping means carried by the other arm, said clamping means exerting and maintaining a yielding vertical pressure on the messenger wire when 45 the hanger is applied.

2. A cable hanger constructed of a single piece of material and comprising a number of laterally spaced and curved fingers, arranged to support, but not surround a cable, 50 an arm carried by each of the outermost ones of said fingers, a hook carried by one of said arms, and a yielding clamping means carried by the other arm for preventing creeping of the hanger when applied to the messenger.

3. A cable hanger formed from a single piece of spring wire comprising a body portion affording a seat for a cable, arms carried by the body portion bent outwardly and 60 spaced apart so that the hanger may be applied to an existing cable, without spreading the arms apart, one of said arms provided with a hook adapted to engage a span wire on its top surface at a point beyond the arm 65 by which it is carried and with a substan-

tially straight and yielding portion intermediate said hook and the cable supporting seat, said portion being of greater length than the diameter of the span wire and arranged to engage said wire on its underneath surface, 70 and the other of said arms being provided with a hook arranged at an angle to the first mentioned hook adapted to engage the span wire on its top surface.

4. As a new article of manufacture, a 75 cable hanger formed from a single piece of resilient material, one end being provided with a suspending hook terminating in a lever arm adapted to be positioned beneath a messenger wire, a body portion formed of 80 a series of suspension points or surfaces arranged at an angle to the axis of the messenger and a cable to be supported thereby, the other end of the hanger terminating in a hook spaced apart from the first mentioned 85 hook, thus affording an increased leverage by means of which the hanger may be applied to or removed from the messenger wire.

5. A cable hanger comprising a cradle like body, open topped, whereby a cable may 90 be supported thereupon without threading the cable through the device, a suspending arm at each end of the device, a hook at the end of one arm at approximately right angles to the longitudinal axis of the device, a 95 wrist at the free end of the other suspending arm and a hook at the free end of said wrist arranged at an angle other than a right angle to the longitudinal axis of the device.

6. A cable hanger formed from a single 100 piece of spring wire comprising a body portion in a series of loops in plan and upwardly curved in end elevation, the free ends of said body portion terminating in hooks adapted to engage a supporting wire, and a 105 substantially straight portion formed intermediate of one of said hooks and the body portion, and being of greater length than the diameter of the supporting wire, and arranged to engage the supporting wire at an 110 angle other than a right angle.

7. A cable hanger formed from a single piece of elastic wire comprising a cable supporting seat, outwardly curved and spaced apart arms carried by said seat so that the 115 hanger may be introduced over an existing cable, without springing the arms apart, one of said arms being provided with a substantially straight and yielding portion terminating in a hook adapted to engage a span 120 wire at a point above and beyond the point of engagement of said portion with the span wire, the overlying portion of the hook and the substantially straight and yielding portion being arranged at an angle to each 125 other, and the other of said arms being provided with a hook adapted to engage the top surface of a span wire, said hooks and the substantially straight portion lying beneath the span wire, exerting a constant yielding 130

vertical pressure on the span wire and preventing it from creeping.

8. A cable hanger formed from a single piece of spring wire comprising a body portion affording a seat for a cable, outwardly bent and spaced apart arms carried by the body portion so that the hanger may be applied to the span wire over an existing cable without spreading the arms, one of said 10 arms provided with a hook adapted to engage a span wire on its top surface at a point beyond the arm by which it is carried and with a yielding portion intermediate said hook and the cable supporting seat adapted 15 to engage said wire on its underneath surface, the said yielding portion and the overlying portion of said hook being arranged at an angle other than a right angle to the longitudinal axis of the messenger or the 20 span wire, and the other of said arms being provided with a hook adapted to engage the span wire and to exert a downward pressure thereon.

9. A cable hanger formed of a single piece 25 of spring wire having an elongated cradle-like seat in which the cable lies, open at the top so as not to surround the cable, suspension arms extending from the ends of the cable seat, whereby they are widely separated from each other, permitting the hanger 30

to be applied to a cable already strung, and the ends of the arms respectively carrying means to engage with a messenger wire.

10. A cable hanger formed of a single piece of elastic wire having an elongated 35 cradle-like seat in which the cable lies, open at the top so as not to surround the cable, suspension arms extending from the ends of the said support, whereby they are widely separated and arranged to lie on opposite 40 sides of the suspended cable to which the hanger is applied, thus permitting the hanger to be applied and removed from a cable already strung, and the ends of the suspension arms being formed into hooks constituting seats adapted to receive a messenger 45 wire to which the hanger is applied, the said seats being out of line with each other when the hanger is removed from the messenger wire, whereby the application of the hanger 50 thereto twists the hanger and causes the said hooks to exert a clamping action preventing longitudinal movement of the hanger.

In testimony whereof I have signed my name to this specification in presence of two 55 subscribing witnesses.

JASPER BLACKBURN.
